UNITED STATES PATENT OFFICE.

FRANZ BELT, OF VIENNA, AUSTRIA.

PULLEY-BLOCK.

1,241,489.

Specification of Letters Patent.

Patented Oct. 2, 1917.

Application filed July 6, 1916, Serial No. 107,762. Renewed May 24, 1917. Serial No. 170,780.

To all whom it may concern:

Be it known that I, FRANZ BELT, manufacturer, subject of the Emperor of Austria, residing at IV Karolinengasse 23, Vienna, 5 Austria, have invented certain new and useful Improvements in Pulley-Blocks, of which the following is a specification.

The present invention relates to pulley blocks and the object is to provide a block 10 which can be easily made in masses and consequently will be cheaper to produce than hitherto. According to the present invention the parts forming the housing of the block are stamped or pressed of sheet metal 15 and assembled and attached together as and in the manner hereinafter particularly set forth.

In the accompanying drawing a pulley made according to the invention is illustrated in two modifications.

Figure 1 is a sectional elevation of the improved block having four pulley wheels, Fig. 2 is a side elevation of Fig. 1 with the top part in section, Figs. 3 and 4 are 25 similar views respectively of a block having a single pulley wheel. Figs. 5 and 6 are a plan view and central cross section respectively of the part of the housing made by stamping or pressing, of the block shown in 30 Figs. 1 and 2 and Figs. 7 and 8 are similar views of the suspending parts of the block.

As illustrated in Figs. 1 and 2 the block consists of the housing member 1 in which the pulley wheels or rolls 2 are mounted 35 in the known manner between partition disks 3. The housing proper consists of a pressed sheet metal body 4 of the form shown in Figs. 5 and 6 before it is bent into its final shape. The central part of the 40 blank has its edges turned or folded around at 4 and is provided at its ends with holes 5 and 6 for the spindle 7 of the pulley wheels and the cross bolt or rivet 8 to which the end of the rope is attached.

45 The suspending member 10 forms the other part of the block, this member also being stamped of sheet metal and having the form illustrated in Fig. 7, the edges of the same being folded around as illustrated 50 at 11, 11 in Fig. 7. This part is also pro-

vided with holes 12 at each end through which the spindle or axle pin 7 passes, and in which its ends are secured.

The parts are assembled as illustrated in Figs. 1 and 2 in the following manner:— 55

The main plate 1 of the housing is first bent to the desired shape (Fig. 1) and then the axle 7 is passed through the holes 5. The plate 10 is then passed with its flanged edges over the central part of the plate 1 60 and the two parts pressed and riveted together.

The pulley block thus formed is of great strength and very light construction.

The single pulley block illustrated in 65 Figs. 3 and 4 is made in the same manner.

I claim as my invention:—

1. A pulley block consisting of a sheet metal housing having depending members in and between which the axle for the pulleys is attached, the said members having their edges folded one over the other to form the upper bow of the pulley substantially as described. 70

2. A pulley block having a sheet metal housing consisting of depending side members between which the rolls are mounted, a bow connecting the two depending members and having its edges turned upwardly and a second member having depending 80 arms to fit over the said first member and downwardly bent edges at its bow part to engage those of the first member. 75

3. A pulley block having a sheet metal housing consisting of an inner member having flat sides and a connecting bow part having upwardly turned edges and an outer member having flat sides to engage over the sides of the inner member and a connecting bow part between the two sides having 90 downwardly turned edges to engage with the edges of the inner member and a pivot to connect the two parts and support the pulley rolls substantially as described. 85

In testimony whereof I affix my signature 95 in presence of two witnesses.

FRANZ BELT.

Witnesses:

ANTON MAREK,
AUGUST FUGGER.
